UNITED STATES PATENT OFFICE.

THOMAS J. LOVETT, OF CHICAGO, ILLINOIS.

DESIGN FOR A VEHICLE-WHEEL.

SPECIFICATION forming part of Design No. 27,759, dated October 19, 1897.

Application filed August 6, 1897. Serial No. 647,386. Term of patent 14 years.

To all whom it may concern:

Be it known that I, THOMAS J. LOVETT, a citizen of the United States, residing at Chicago, in the county of Cook and State of Illinois, have invented and produced a new and original Design for Vehicle-Wheels, of which the following is a specification, reference being had to the accompanying drawings, forming part thereof.

Figure 1 is a side elevation of a vehicle-wheel, showing my new design; and Fig. 2 shows the form of the peripheral portion in cross-section.

As shown in the drawings, the leading or

material feature of my design consists of the inner rounded surface A, the plain sides B, the convexities C, extending beyond the planes of the sides B, and the convex outer or tread surface D, presenting radial lines *ee*.

Having described my invention, what I claim as new, and desire to secure by Letters Patent, is—

The design for a vehicle-wheel, substantially as herein shown and described.

THOMAS J. LOVETT.

In presence of—

J. H. LEE,
E. B. KIRBY.
